United States Patent Office

Des. 177,223

Patented Mar. 27, 1956

177,223

PAPER WEIGHT OR THE LIKE

Oscar G. Evans, Danville, Va.

Application January 5, 1955, Serial No. 33,832

Term of patent 14 years

(Cl. D74—12)

Fig. 1 is a side elevational view of a paper weight showing my new design;

Fig. 2 is a top plan view thereof;

Fig. 3 is an end elevational view; and

Fig. 4 is a perspective view thereof.

I claim:

The ornamental design for a paper weight or the like, as shown.
